UNITED STATES PATENT OFFICE.

GEORGE ANTON, OF MONONGAHELA CITY, PENNSYLVANIA.

MINER'S LAMP.

SPECIFICATION forming part of Letters Patent No. 431,734, dated July 8, 1890.

Application filed January 24, 1890. Serial No. 337,975. (No model.)

To all whom it may concern:

Be it known that I, GEORGE ANTON, a citizen of the United States, residing at Monongahela City, in the county of Washington and State of Pennsylvania, have invented certain new and useful Improvements in Miners' Lamps; and I do hereby declare that the following is a full, clear, and exact description of the invention, which will enable others skilled in the art to which it appertains to make and use the same, reference being had to the accompanying drawings, which form a part of this specification.

When made of sheet metal, these lamps have heretofore been constructed with their bodies and bottoms formed separate and connected by a soldered joint; but the rough usage to which these articles are exposed frequently causes an opening at this joint, which causes the lamp to leak, to the discomfort of the miner. To remove the wick or draw it farther out of the wick-tube, the miner inverts the lamp, and, grasping the hook at its rear side, strikes the front edge of the bottom sharply on the edge or corner of any suitable object. This action jars the wick out of the tube, but at the same time is liable to, and does eventually, separate the bottom from the body.

The joint at the bottom of the lamp is usually formed by bending the periphery or edge of the bottom up against the outer surface of the body, thereby forming a projecting flange or rib, which serves to enable the miner to strike a firm blow, and thereby quickly and effectually jar the wick into the desired position. It is desirable, therefore, to provide lamps with this projecting flange or rib, as it is of advantage to the miner; but it will be readily seen that when said flange or rib is formed by the joint between the body and the bottom of the lamp an opening is soon effected and the lamp is rendered useless.

The object of my invention is to provide a lamp which has the advantage of the above-mentioned flange or rib, but is not open to the disadvantages referred to in connection therewith, and this object I attain by forming the bottom and body of the lamp from a single sheet of metal by drawing, stamping, or pressing.

In the accompanying drawings is illustrated a lamp made in accordance with my invention, in which—

Figure 1 is a side view thereof. Fig. 2 is a vertical central sectional view of the same, and Fig. 3 is a side view of a lamp the body of which has a slightly different form.

The body A of the improved lamp may be formed integral with the bottom B thereof by means of a draw-press, which will produce the desired form from a single flat sheet of metal. Around the periphery of the said bottom, at the junction of the latter with the side or body of the lamp, is a rounded rib C, which projects out slightly beyond the surface of the body and performs the same function as the corresponding flange or rib which has been referred to in connection with the ordinary forms of lamps, in which the body and bottom are formed from separate pieces, with a joint at the angle—namely, this flange or rib C enables the miner to jar the wick out of the wick-tube by striking the same on a projecting edge or corner of any suitable object. In this improved form of lamp, however, the objection heretofore urged in connection with the ordinary form of lamps is overcome—namely, the separation from the body of the bottom. It will be seen that this cannot result from blows struck on this projecting flange or rib, because there is no joint. Thus I still retain the advantages of the flange or rib in my improved lamp, and at the same time overcome the disadvantages connected therewith by forming the body and bottom integral by drawing, stamping, or pressing, and forming said flange or rib integral with the body and bottom by the same operation. The wick-tube is also preferably drawn in the same manner as the body of the lamp, and thereby formed without the joint, which usually extends from one end thereof to the other. In the ordinary forms of lamps this wick-tube is provided with a soldered joint, which is liable to be opened by the melting of the solder.

In Fig. 3 I show a different shape of lamp-body; but it will be understood that any preferred form of body may be produced by the same process as described—namely, drawing.

I am aware that heretofore various utensils and articles have been formed with their sides and bottom integral by casting; but I have demonstrated to my satisfaction that this manner of constructing miners' lamps is impracticable from the very obvious fact that the

casting cannot be made thin enough to form a lamp which will be light enough to carry upon the hat. The metal will not flow thin enough to form a lamp which can be carried 5 in this way. Furthermore, I am aware that various articles have been formed from drawn metal, with their sides and bottom integral; but I do not claim this, broadly. I do not desire to claim the method of constructing vessels with their sides and bottom integral, consisting in drawing, stamping, or pressing, for I am well aware that this is not new; but from the foregoing description it will be readily understood that my invention consists solely 10 in constructing a miner's lamp in a peculiar way, whereby the joint at the bottom is dispensed with without dispensing with the very necessary and useful flange or rib. This manner of forming the lamp with a rounded flange 15 or rib, which, obviously, is hollow, dispenses 20

with all angles, and therefore prevents the accumulation of dirt and enables the lamp to be readily cleaned.

It will be understood that my improved lamp may be made of any suitable sheet metal—as 25 brass, copper, tin, &c.

Having thus described my invention, what I claim, and desire to secure by Letters Patent of the United States, is—

A miner's lamp formed from a single sheet 30 of metal by drawing, pressing, or stamping, provided with an integral hollow projection or flange flush with the bottom, substantially as described.

In testimony whereof I affix my signature in 35 presence of two witnesses.

GEORGE ANTON.
